UNITED STATES PATENT OFFICE

2,477,060

WATER-COOLED SLAB MOLD

Frank J. Hudak, Torrington, Conn., assignor to
The Torrington Manufacturing Company, Tor-
rington, Conn., a corporation of Connecticut

Application September 10, 1945, Serial No. 615,369

4 Claims. (Cl. 22—153)

1

This invention relates to water cooled or chill slab molds such as are extensively used for casting slabs of metal, particularly copper-bearing alloys, which are subsequently reduced to sheets by rolling.

In general water cooled slab molds of this type comprise a stationary mold back or body and a complementary mating mold front or cover hinged to the mold body and capable of being swung horizontally through an arc of 90° or more. When closed the mold body and the mold cover provide a mold cavity and clamping devices are provided for forcing the cover into firm contact with the body and for holding it in such contact during casting. The mold cavity is provided with lining plates of a material having good heat conductivity, usually copper. Provision is made for circulating water or other cooling medium through the body and through the cover in contact with the lining plates so that the plates are enabled to rapidly conduct heat away from the metal constituting the slab. Thus the slab is rapidly cooled and can be removed from the mold after a very brief cooling interval.

In order that the hinges for the cover may not interfere with the operation of the clamping devices in drawing the cover into firm contact with the body, it has been the usual prior practice to provide a limited amount of looseness in the hinge joints. The provision of looseness in the hinge joints, while effective to permit the movement of the cover under the influence of the clamping means, is objectionable as the hinges having such loose joints cannot support the cover in level position and in proper alignment or register with the body. The side of the cover opposite the hinges sags and the cover does not correctly register with the body when the cover is clamped in closed position. To avoid such sagging it has been the practice, in some instances, to provide means additional to the hinges, such as rollers on the bottom of the cover, to support the cover and hold it level and in correct alignment with the body. Such additional means are expensive, cumbersome and inconvenient.

To avoid the objections last above stated, it has been heretofore proposed to provide a hinge wherein the body-connected hinge element carried a round pivot pin in fixed vertical position and wherein the cover-connected hinge element was provided with a pin receiving slot extending in the direction perpendicular to the face of the cover. This construction, while perhaps theoretically advantageous, was subject to

2

the objection that there was only line contact between the stationary pivot pin and the walls of the slot. The parts were therefore readily subject to wear and proper lubrication could not be maintained.

The principal object of the present invention is to provide a mold of the class mentioned wherein the pivot member on each body-connected hinge element is rotatable with respect thereto and is provided with horizontally extending guiding surfaces and wherein each cover-connected hinge element has horizontally extending guiding surfaces engaging those of the corresponding pivot member and positioned perpendicularly to the face of the cover. Thus the interengaging guiding surfaces are always perpendicular to the cover face and they permit the cover to be moved horizontally to effect clamping. The said interengaging guiding surfaces serve in all positions of the cover to prevent any movement thereof in directions parallel to its face.

Still other objects of the invention will be apparent from the accompanying drawings and from the following specification and claims.

25 Of the drawings:

Fig. 1 is a front view of a mold embodying the invention.

Fig. 2 is a side view of the mold with a portion broken away and shown in vertical central section.

Fig. 3 is a plan view.

Fig. 4 is an enlarged fragmentary plan view showing one of the hinges to which the invention more particularly relates.

Fig. 5 is a view similar to Fig. 4 but with the cover in open position.

Fig. 6 is an enlarged fragmentary side view taken partly in section along the line 6—6 of Fig. 1.

40 The mold comprises a normally stationary body 10 which is recessed to form the back wall, the side walls and the bottom wall of a mold cavity which is open at the top. The body 10 may be provided with a foot or base 12 by means of which it may be supported on and secured to a suitable floor or platform. The mold also comprises a front member or cover 14 which is hinged to the body for movement about a vertical axis and which when in closed position forms the front wall of the mold recess. The cover 14 is connected with the body 10 by means of two similar hinges 16 and 18, each comprising a hinge element 20 connected to the body, and a hinge element 22 connected to the cover. Each hinge also comprises a vertical pivot member or pin 14. The two

hinges 16 and 18 will be hereinafter described in greater detail.

The body is preferably provided with a back liner plate 26 formed of copper and with side liner plates 28 and 30 also formed of copper. The cover 14 preferably carries a front liner plate 32 similar to the back liner plate 26.

The body 10 is preferably provided with vertically extending channels 34 having horizontal ribs 36 therein, and provision is made for circulating water or other cooling liquid through these channels to conduct heat away from the back liner plate 26. As shown, the cooling liquid is supplied through two pipes 38, 38 and withdrawn through a pipe 40. Vertical channels for cooling liquid may also be provided adjacent the side liner plates 28 and 30. However, such channels constitute no part of the present invention and the said channels, together with the piping therefor, are omitted from the drawings.

The cover 14 is preferably provided with vertically extending channels 42 having horizontal ribs 44 therein and provision is made for circulating water or other cooling liquid through these channels to conduct heat away from the front liner plate 32. As shown, the cooling liquid is supplied through two pipes 46, 46 and withdrawn through a pipe 48. Inasmuch as the cover is movable about the axis of the hinges 16 and 18, the liquid is supplied to the several pipes 46, 46 and 48 through movable connections which permit cover movement and preferably through swivel connections having their axes in alignment with the hinge axis. As shown, the pipes 46, 46 are connected with a pipe 50 which receives liquid through a swivel joint 52, the axis of this swivel joint being in alignment with the hinge axis. The pipe 48 is connected with a pipe 54 which discharges liquid through a swivel joint 56, the axis of this swivel joint being also in alignment with the hinge axis. It will be seen that the described pipe connections permit the cover to be swung about the hinge axis without disturbing or interrupting the flow of liquid through the cooling channels and the cover.

Suitable means are provided for clamping the cover in its closed position, as shown in Figs. 1, 2 and 3 and also in Fig. 4. This clamping means may be widely varied without departing from the invention, but as shown, the said means comprises two vertical series of bolts 58 at opposite sides of the mold. Each bolt is entered in a slot 59 in a flange on the body and is provided with a vertically extending cylindrical head engaging the flange above and below the slot. The bolt is held in place by clips 60 which embrace the cylindrical head of the bolt. It will be seen that the clips hold the bolt in place but nevertheless permit it to be swung laterally about a vertical axis. Each bolt at its front end is adapted to enter a corresponding slot 61 in a flange on the cover and is provided with a nut adapted to engage the said cover flange. It will be seen that by turning the nuts on the several bolts 58, 58, the cover 14 can be drawn rearward into firm engagement with the body and can be so held during casting. Upon the completion of casting and after cooling, the bolts can be loosened to permit the cover to be opened to the position shown by dot-and-dash lines in Fig. 3, and the completed slab can then be removed.

The side liner plate 30 preferably terminates below the top of the mold and in the space immediately above the top of the said liner plate

there is provided a spout 62 to permit the overflow of molten metal when the said metal reaches the level of the spout. An overflow box 64 is provided, this being shown as hinged to the cover 14. The overflow of metal from the spout into the said box serves as an indication that the mold has been completely filled.

In pouring molten metal into the mold use is preferably made of a runner box 66 which rests upon the top edges of the liner plates 26 and 32. This runner box has one or more apertures in the bottom thereof, and these control and direct the flow of the molten metal into the interior of the mold. The runner box is removed before the cover is opened.

Reference will now be had particularly to Figs. 4 to 6 which show in greater detail the before-mentioned hinges of the mold. The before-mentioned pivot member 24 is carried by the body-connected hinge element 20 and is rotatable relatively thereto about a vertical axis. The pivot member 24 has horizontally extending guiding surfaces. Preferably, the pivot member 24 is a pin extending upward from the hinge element, being supported and guided therein by an anti-friction bearing such as a roller bearing 68. The outer race of the bearing 68 is held in place in the hinge element 20 by means of a ring 70 and the inner race of the bearing 68 is held in place on the pin 24 by means of a disc 72. When the pivot member 24 is a pin as described, the aforesaid horizontally extending guiding surfaces are opposite parallel flat vertical faces 14, 14 formed thereon.

The cover-connected hinge element 22 is adapted to engage the pivot member 24. It is provided with horizontally extending guiding surfaces which engage the guiding surfaces on the pivot member and which are perpendicular to the inner face of the cover. By reason of the interengaging guiding surfaces the pivot member is rotatively moved when the cover is swung toward or from its closed position. Inasmuch as the guiding surfaces are always perpendicular to the cover face, the cover can be moved in the direction of the said guiding surfaces and perpendicularly to its inner face, but it cannot be moved in a direction parallel to its inner face.

When the pivot member 24 is a pin, as is preferred, the cover-connected hinge element 22 has an aperture 74 into which the pin extends. The diameter of the aperture is somewhat larger than the diameter of the pivot pin, and the interior of the aperture is provided with two opposite flat faces 76, 76 which engage the flat faces 14, 14 on the pin. The flat faces 76, 76 constitute the before-mentioned guiding surfaces on the hinge element 22. Preferably, the flat faces in the aperture 74 are on separate shoes 78 located in the aperture and held in place by means of screws 80, 80.

At least one of the hinges 16 and 18, preferably the lower hinge 18, is provided with a ball thrust bearing 82 which serves to carry the weight of the cover while permitting it to swing freely when required. An additional thrust bearing in the hinge 16 may also be provided, but ordinarily this is not necessary. The upper race 84 of the bearing 82 is mounted in fixed relationship with the hinge element 22 and the lower race 86 is mounted in fixed relationship with the hinge element 20. Interposed between the two races 84 and 86 is an annular series of balls held in a cage 88. The races 84 and 86 are flat and the cage 88 is therefore free to float horizontally within narrow lim-

its thus permitting the upper race 84 and the hinge element 22 to freely move bodily with respect to lower race 86 and the hinge element 20.

Upon the completion of the casting of the slab and upon sufficient cooling thereof, the runner box 66 is removed and the bolts 58, 58 are loosened, and the cover is swung forward to the position shown by dot and dash lines in Fig. 3 and shown by full lines in Fig. 5. The completed slab is then removed and the cover is closed preparatory to the casting of the next slab. In order that the cover may properly engage the body, it is necessary that it be held by the hinges in level position and in proper alignment with the body without any sagging of the side thereof remote from the hinges, in this case the right side. If the cover were to sag, this would tend to prevent the entry of the front liner plate 32 into its recess in the body; and it would tend to prevent the proper alignment and engagement of the bolts 58 or other clamping means. Furthermore, any misalignment of the cover with the body would leave the top edges of the plates 26 and 32 out of register, with the result that the runner box 66 could not be properly supported.

While it is necessary for the cover to be held in proper aligned position for the reasons stated, it is also necessary for it to be freely movable rearward, without restriction by the hinges, under the influence of the bolts 58, 58 or other clamping means. The construction which has been shown and described fully attains these results. With the cover in or near its closed position, and before the clamping means are applied, it is freely movable forward and backward within the limits determined by the difference between the diameter of the pivot pin 24 and the diameter of the aperture 67. The described pipe connections are sufficiently flexible to permit such forward and backward movement of the cover. The support of the cover on the ball bearing 82 facilitates such forward or backward movement. However, while the cover is free to move forward or backward, it is positively held against lateral movement and against sagging, by reason of the engagement of the flat faces 76, 76 of the shoes 78, 78 with the flat faces 74, 74 of the pivot pin 24. The engagement between the shoes 78, 78 and the flat faces of the pivot pin does not in any way interfere with the swinging movement of the cover, as the pivot pin 24 is freely movable about its vertical axis, being supported for such movement by means of the bearing 68.

Inasmuch as the pivot members 24, 24 are rotatable, the bearings 68 in which they are supported carry the weight of the cover 32 during swinging thereof and all rotary movement at the hinges is between the elements of the said bearings. There is no rotary movement of the cover connected hinge element 22 relatively to the pivot member 24, and the former moves relatively to the latter only to a very limited extent horizontally. The guiding surfaces on the pivot members 24 and on the hinge element 22 are ample in area and there is little or no tendency for them to wear.

It will be observed that the hinges serve to hold the cover level in all positions thereof. It is not only held level when parallel with the body or in closed position as already described, but inasmuch as the hinge elements are rotatable with the cover the said cover is also held level in all other positions thereof. This makes it unnecessary to provide any track or other support for the cover additional to the hinges.

What I claim is:

1. In a mold for casting brass and the like, the combination of a mold body open at one side, a vertical cover having an inner face adapted to engage the open side of the body to close it, means for clamping the cover in its body closing position, two vertically spaced hinge elements connected with the body, two pivot members mounted on the respective body-connected hinge elements for relative rotative movement about a fixed vertical axis and each having two parallel flat vertical faces, and two vertically spaced cover-connected hinge elements adjacent the respective body-connected hinge elements and each having two parallel flat vertical faces which are perpendicular to the inner face of the cover and which engage the flat faces of the corresponding pivot member to cause rotative movement thereof in unison with the cover when the latter is swung horizontally toward or from its body closing position, the said cover-connected hinge elements permitting movement of the cover in the direction of the said interengaging flat faces and perpendicularly to the inner face of the cover and also serving to narrowly limit such movement and the said cover-connected hinge elements in all positions of the cover serving by reason of the said interengaging flat faces to prevent movement of the cover parallelly with the inner face thereof.
2. In a mold for casting brass and the like, the combination of a mold body open at one side, a vertical cover having an inner face adapted to engage the open side of the body to close it, means for clamping the cover in its body closing position, two vertically spaced hinge elements connected with the body, two pivot pins mounted on the respective body-connected hinge elements for relative rotative movement about a fixed vertical axis and each having two parallel flat vertical faces, and two vertically spaced cover-connected hinge elements adjacent the respective body-connected hinge elements and each having a pin receiving aperture provided with two parallel flat vertical faces which are perpendicular to the inner face of the cover and which engage the flat faces of the corresponding pivot pin to cause rotative movement thereof in unison with the cover when the latter is swung horizontally toward or from its body closing position, the dimensions of the apertures in the direction of the interengaging flat faces being slightly greater than the corresponding dimensions of the pins so as to permit narrowly limited movement of the cover perpendicularly to the inner face of the cover and the said interengaging flat faces in all positions of the cover serving to prevent movement of the cover parallelly with the inner face thereof.
3. In a mold for casting brass and the like, the combination of a mold body open at one side, a vertical cover having an inner face adapted to engage the open side of the body to close it, means for clamping the cover in its body closing position, two vertically spaced hinge elements connected with the body, two pivot pins mounted on the respective body-connected hinge elements for relative rotative movement about a fixed vertical axis and each having two parallel flat vertical faces, two vertically spaced cover-connected hinge elements adjacent the respective body-connected hinge elements and each having a pin receiving aperture with a diameter slightly greater than the diameter of the corresponding pin, and two oppositely disposed shoes in each

aperture having parallel flat vertical faces which are perpendicular to the inner face of the cover and which engage the flat faces of the corresponding pivot pin to cause rotative movement thereof in unison with the cover when the latter is swung horizontally toward or from its body closing position, the said interengaging flat faces on the pins and on the shoes serving in all positions of the cover to prevent movement of the cover parallelly with the inner face thereof.

4. In a mold for casting brass and the like, the combination of a mold body open at one side, a vertical cover having an inner face adapted to engage the open side of the body to close it, means for clamping the cover in its body closing position, two vertically spaced hinge elements connected with the body, two pivot pins mounted on the respective body-connected hinge elements for relative rotative movement about a fixed vertical axis and each having two parallel flat vertical faces, two vertically spaced cover-connected hinge elements adjacent the respective body-connected hinge elements and each having a pin receiving aperture provided with two parallel flat vertical faces which are perpendicular to the inner face of the cover and which engage the flat faces of the corresponding pivot pin to cause rotative movement thereof in unison with the cover when the latter is swung

horizontally toward or from its body closing position, the dimensions of the apertures in the direction of the interengaging flat faces being slightly greater than the corresponding dimensions of the pins so as to permit narrowly limited movement of the cover perpendicularly to the inner face of the cover and the said interengaging flat faces in all positions of the cover serving to prevent movement of the cover parallelly with the inner face thereof, and a ball thrust bearing interposed between one cover-connected hinge element and the corresponding body-connected hinge element, the said bearing having flat ball engaging races which permit the cover-connected hinge element to move both rotatively and horizontally.
